LOUD SPEAKER

Filed March 8, 1927

Inventor
Sherm J. Offerle.

By *Clarence A. O'Brien*
Attorney

UNITED STATES PATENT OFFICE.

SHERM J. OFFERLE, OF WARREN, PENNSYLVANIA.

LOUD-SPEAKER.

Application filed March 8, 1927. Serial No. 173,738.

This invention relates to loud speakers, particularly adapted for use with radio sets.

An object of the invention resides in providing a radio loud speaker which is con-

5 structed so that it may be hung or suspended on the cabinet of a radio set and preferably along the back side thereof, so that the sound outlet opening in the head of the speaker is immediately above the cabinet for directing 10 the sound outwardly, over the front portion of the cabinet, making it considerably easier in operating the set to tune in a station.

A further object of the invention resides in 15 providing a loud speaker construction for radio sets which may be hung on the cabinet of the set and is adapted to be constructed and entirely of wood, having a sound amplifying chamber of rectangular section which is hung on the radio cabinet and suitably in- 20 sulated therefrom to prevent vibration in the set being transmitted to the sound amplifying chamber.

The invention comprehends numerous other 25 objects which reside in the specific construction and relation of the parts as more particularly pointed out in the following detailed description and in the claims directed to the preferred form of the invention, it being understood, however, that various changes in 30 the size, shape and relation of the parts may be made without departing from the spirit and scope of the invention as herein set forth.

In the drawings forming part of this application;—

35 Figure 1 is a front elevation of a radio cabinet having the loud speaker constructed in accordance with the invention applied thereto.

40 Fig. 2 is an end elevation of the radio cabinet showing the loud speaker construction in vertical transverse section.

Fig. 3 is a detail sectional view taken on the line 3—3 of Fig. 1.

45 The cabinet of a radio set is indicated at 1 having the top 2 as usual, on the rear edge of which is supported the improved loud speaker construction of this invention, generally indicated by the numeral 3.

50 This loud speaker construction includes a head 4 which is comprised of the front plate member 5 and the rear plate member 6 secured in spaced parallel relation by the frame 7 secured to the edge portions thereof. Felt pads 8 are secured on the lower faces of the

55 frame 7 adjacent the opposite end thereof

as shown in Fig. 1, for engagement with the top 2 of the radio cabinet, by which the loud speaker is supported in insulated relation on said cabinet.

The central portion of the head 4 is provided with a rectangular opening, in which is mounted the horn structure 9. The upper enlarged end of the amplifying horn structure is mounted in the head 4 and the open end thereof is provided with a suitable screen 60 or cover of silk or the like indicated at 10, which will not interfere with the sound but prevent dust from entering the interior of the amplifying horn and at the same time improve the appearance of the loud speaker. 65

This horn structure is formed of a main body 11, while the portion secured in the head 4 extends laterally from the main body as indicated at 12 in Fig. 2. The main body 70 as well as the portion 12 of the horn are 75 of rectangular cross section and of gradually increasing size from the lower toward the upper end thereof. The rear wall 13 is provided with the curved portion 14 at the upper end thereof, merging into the upper 80 wall of the lateral extension 12 secured in the head.

The lower end of the horn is provided with a suitable opening to receive the extension 15 on the reproducer unit 16 of any suitable and 85 desired character known in the art for electrically reproducing sound waves. The reproducer has communication with the interior of the horn structure 9, so that the sound waves are provided and projected, and the air column within the horn vibrated in 90 reproducing and amplifying the sound. This horn is constructed preferably, of wood, known to have greater resonance and tone 95 amplifying qualities than other materials, and it is desired to use the types of hard-wood which are known to be best adapted in constructing horns of this character.

The tapered structure of the horn body 100 from the lower end to the upper end thereof, is of such a character as to adapt it to properly and uniformly amplify sound waves of audible frequency. A felt pad 17 is secured to the lower end of the horn body 9 and forms a third point of suspension for the 105 loud speaker, so that the entire body of the horn is hung in spaced relation on the cabinet of the radio set.

With this construction, a highly novel 110 combination has been provided in which the

cabinet of a radio set is used as a base for supporting the loud speaker, which is hung instead of mounted on the cabinet, in such a manner that the reproducing body is freely suspended in order that it may have a free resonating action in the amplification of sound waves produced therein by the operation of the reproducer unit 16.

With the outlet end opening forwardly at 10 the rear of the radio cabinet, so that in tuning the set to any desired station, the loud speaker unit is in proper position for the operator of the set to conveniently tune in a selected station. This loud speaker construction 15 further cooperates with the radio set to produce a compact and novel association of the parts, at the same time presenting a highly desirable finish and appearance of the set.

Having thus described my invention, what 20 I claim as new is:—

1. A loud speaker unit comprising a horn having its bell end disposed horizontally and its opposite end disposed vertically and adapted for support with respect to the similarly disposed surfaces of a cabinet, a head 25 extending transversely at opposite sides of

said bell end and resilient pads interposed between the ends of the head and the horizontal surface of the cabinet and between the vertical section of the horn and the vertical surface of the cabinet whereby to suspend the horn in spaced relation therefrom. 30

2. A loud speaker unit comprising a horn having its bell end disposed horizontally and its opposite end disposed vertically and adapted for support with respect to the similarly disposed surfaces of a cabinet, a head formed at the bell end of the horn extending transversely at opposite sides thereof and composed of front and rear spaced parallel 40 vertically extending plate members, open along their lower edges, said rear plate member having an opening with the bell end of the horn fitted therein and said front plate member having a similar opening aligned therewith, said plate members and said vertical section of the horn having a resilient pad interposed between the respective adjacent surfaces of the cabinet whereby to support the unit in spaced relation therefrom. 45 50

In testimony whereof I affix my signature.
SHERM J. OFFERLE.
